UNITED STATES PATENT OFFICE.

BENJAMIN FRANKLIN HAYS, OF NEW YORK, N. Y.

DESIGN FOR A BOTTLE AND STOPPER THEREFOR.

41,560.

Specification for Design.

Patented July 11, 1911.

Application filed July 2, 1909. Serial No. 505,761. Term of patent 14 years.

To all whom it may concern:

Be it known that I, BENJAMIN FRANKLIN HAYS, a citizen of the United States, and a resident of the borough of Brooklyn, city of New York, in the county of Kings and State of New York, have invented a new, original, and ornamental Design for a Bottle and Stopper Therefor, of which the following is a specification, reference being had to the accompanying drawings, forming part thereof.

The leading feature of the design consists in a cross sectionally rectangular bottle body having one side provided with longitudinal ribs throughout, and the other three sides having plain faces and marginal ribbed sec-

tions at the ends of said faces; and the stopper having its head provided with a saw toothed periphery.

In the drawings,—Figure 1 is a perspective view of a bottle and stopper therefor showing my new design. Fig. 2 is an elevation thereof.

I claim:

The ornamental design for a bottle and stopper therefor as shown and described.

In testimony whereof, I have affixed my signature in the presence of two witnesses.

BENJAMIN FRANKLIN HAYS.

Witnesses:

EGBERT W. NELSON,
FRANCES D. TURITZ.
